J. S. WILLIAMSON

FOLDING SHIPPING CASE

Filed May 5, 1925

UNITED STATES PATENT OFFICE.

JOHN S. WILLIAMSON, OF SEATTLE, WASHINGTON.

FOLDING SHIPPING CASE.

Application filed May 5, 1925. Serial No. 28,042.

This invention is an improvement in folding shipping cases and, more especially, to the shipping case illustrated and described in U. S. Patent No. 1,115,759 issued to me

5 November 3, 1914.

The object of the invention is the perfecting of shipping cases of this character to render the same more durable, efficient, convenient and generally useful.

10 More specific objects and advantages of the invention will appear in the following description.

The invention consists in certain novel constructions and combinations of parts hereinafter described and claimed.

Referring to the drawing forming a part hereof,—

Figure 1 is a perspective view of the improved shipping case with the parts arranged for a merchandise container; Fig. 2 is a perspective view showing the tray or base and side sections of the case; Fig. 3 is a vertical longitudinal section through Fig. 1; Fig. 4 is a similar view showing the case in its collapsed condition; Figs. 5 and 6 are vertical transverse sections taken substantially on broken lines 5—5 and 6—6 of Fig. 3; Fig. 7 is a horizontal detail section showing a cover locking device; Fig. 8 is a fragmentary elevational view of the cover to illustrate one of the hinge elements thereof; Fig. 9 is a plan view showing portions of one of the side sections, the partition and the means for detachably coupling the same together; and Fig. 10 is a detail sectional view on line 10—10 of Fig. 3.

The embodiment of the invention in the drawing comprises a case of sheet metal or an equivalent having a base member in the form of a shallow tray consisting of a floor 11, front and rear sides 12 and 13, and ends 14. Hingedly connected as at 15 to the upper edges of the tray sides are front and back side sections 16 and 17, respectively. At each end of a side section and rectangular thereto, it is provided with a flange 18.

Hingedly connected as at 19 to each of the tray ends 14 and at a short distance below the upper edge thereof is an end section 20 having its upper edge 21 in a plane with the upper edges 22 of said side sections or nearly so. As illustrated, each end section 20 is formed adjacent its upper edge to provide a substantially rectangular shaped hollow projection or cleat element 23 extending

horizontally the full width of the end. Said cleat element serves as a hand hold for conveniently carrying the case when the same is arranged as shown in Fig. 1. The upper portion of an end section is, moreover, formed of two thicknesses of material by the provision of a fold 24 upon the inner side of the section to extend downwardly a short distance below the respective cleat element. Below a cleat such fold is welded or otherwise secured to the main portion of the section and coacts with the cleat thereof to render the end section strong and rigid. At each of its ends the cleat 23 is slotted as at 25 (Fig. 10) to permit the upper end of a side-section flange 18 to enter the interstice between said fold and the main portion of an end section above the cleat 23 of the respective section.

Below said cleats, the flanges 18 embrace said end sections by engaging against the outer surface of each as represented in Fig. 1. To prevent the accidental separation of the side sections 12 and 13 from the end sections, I provide latch devices, best shown in Fig. 6, each consisting of a rod 27 movable vertically in an eye attachment 28 of an end section and having at its upper end an offset part 29 which is engageable in a socket attachment 30 of the adjacent side section.

For convenience in engaging and disengaging a latch, the same is desirably provided with a finger gripping projection as 31. As a container for some characters of merchandise, such as eggs for example, the case is advantageously provided at about its midlength with a transverse partition.

For this purpose, there is provided at about the midlength of the tray floor 11 an upwardly extending rib 32 (Figs. 3 and 4) to the upper portion of which is hinged the lower member 33 of a two-part partition. The upper member 34 of the partition is slidably connected to said lower member 33 as by means of bolts 35 (Fig. 5) extending from one of the members through vertical guide slots 36 provided in the other member. Such sliding connection between the partition members permits the partition being contracted to enable it to be folded down into the tray as shown in Fig. 4.

For securing the partition to the side sections 16 and 17 in operating position, I provide upon each of said sections, a bracket piece 37 having a notch 38 therein and offset from the respective section to afford a space

39 therebetween, see Fig. 9 to accommodate arms 40 which extend at right angles from the ends of a tie-rod 41.

This tie-rod is rotatably mounted in a loop 42 provided in the upper end of the partition member 34. To employ the partition-securing means above described, the partition member 34 is regulated with respect to the other member 33 so that when the partition is swung into vertical position the rod 41 will be directly in alignment with the respective bracket notches 38, whereupon the side sections are drawn toward each other causing the rod to enter the notches, after which the rod is turned to carry the arms 40 thereof into the spaces 39 thereby engaging the side sections to the partition. For disengaging the partition from the side sections the operation above described is reversed. Supplementary to such tie-rod connections, I employ at about the midlength of the case latch devices substantially similar to those hereinbefore described with reference to the case corner-connections, namely—latch rods 27¹ movable in eye attachments 28¹ of the partition and each provided with a part 29¹ which is engageable in socket attachments 30¹ of the side sections 16 and 17.

Included in the invention is a cover member for the case, said cover consisting of a top wall 44 from which depend end flanges 45, a front flange 46, and a rear flange 47 at the outside of the respective side and end sections of the case when the latter is in its expanded condition (Figs. 1 and 3), or about the outside of the tray when the case is folded as represented in Fig. 4. Secured to the rear cover-flange 47 is a pair of ears 48 each carrying below the flange, as shown in Fig. 8, a pin arranged to provide a protruding end 49 at each side of the ear.

Such ear-and-pin assemblies constitute hinge elements which are engageable interchangeably either with the rear side-section 17 or with the rear side 13 of the tray by the provision therein of suitably positioned apertures 50 and 51 (Figs. 2 and 3) each of said apertures being of the shape, substantially, of an inverted letter T, permitting a hinge element being inserted through the lower portion of the respective aperture and thence elevated to have the ear within the relatively narrow upper portion, whereupon the pin engages against the inner surface of the side section 17, or the tray side 13, according to which it is desired to attach the cover. Mounted on the front flange 46 of the cover are one or more locking bolts, two being shown, in the nature of thin bars 53 (Fig. 7) which are disposed against the inner surface of the flange and are rigidly coupled by means of rivets 54 passing through slots 55 of the flange, with operating plates 56 which are disposed to be

against the outer surface of the flange. Said bolts are engageable with lips 57 and 57¹ struck out from the case section 16 and from the front wall 12 of the tray at one side of openings 58 and 58¹ provided in the respective section and wall. For locking the cover in place the bolts are by means of the respective operating plates 56 moved laterally of the case into engaged relations with the respective lips as illustrated, for instance, in Fig. 7.

For use in shipping merchandise, the case is arranged with the parts in the relative positions shown in Figs. 1, 3, 5 and 6. The casing sections 16, 17 and 20 are held in place at the case corners by means of their interlocking connections and also by means of the latches 27 and, intermediate the length of the case, by means of the partition 33—34, the tie-rod 41 and latches 27¹.

The cover is openable with respect to the casing body by swinging the cover upwardly about its hinge-pin 49 connections with the rear section 17 of the case. To collapse the case preparatory, for example, for returning the same to a produce shipper for reuse, the cover is removed by first swinging the latter into a substantially vertical position and then disengaging the hinge connections by lowering the same with the cover until the hinge pins are brought into the lower portions of the apertures 50 from which the hinge elements are readily withdrawn.

The partition 33—34 is now disengaged from the side sections 16 and 17, then contracted and swung down into the tray, see Fig. 4. The end sections 20 and the side sections 16 and 17 are now successively turned down into the tray. After this is done the cover is attached at its rear side to the tray wall 13 by its hinge connections being passed through the apertures 51 to engage the inner surface of such tray wall. Finally the cover is swung down into its closed relation with the tray and thereupon is secured at its front side by means of the bolt plates 53 to the front of the tray.

It will be evident from the description that my shipping case is simple and strong in construction and, being free from complications, is not liable to get out of order, either in its expanded or contracted conditions, nor in transforming the same.

What I claim, is,—

1. In a folding shipping-case, a tray base-member, side and end sections hinged to said base-member, bracket devices secured to the respective side sections, a two-part partition having one of its parts hingedly connected to said base-member, means connecting the partition parts with each other for relative sliding movements, means carried by said end sections and by the partition for detachably securing the

- same to the side sections in substantially right angular relations with the latter and also with respect to the floor of the base member, and a tie-rod rotatably connected 5 to one of the partition parts, said tie-rod having bent ends engageable with the bracket devices of both of said side sections.
2. A folding shipping case comprising a hollow base member, side and end sections 10 hinged to the base member to fold into the latter, means for detachably connecting the end and side sections together at the case corners for detachably retaining said sections in upright positions, one of said side sections and the subjacent wall of the base 15 member being respectively provided with apertures of substantially the shape of an inverted letter **T**, a cover member, and means provided upon said cover and engageable within the apertures of the re- 20 spective side sections and also within the apertures of the base member for hingedly connecting the cover to either the section referred to or to the base, selectively.

Signed at Seattle, Washington, this 21st 25 day of April 1925.

JOHN S. WILLIAMSON.
